UNITED STATES PATENT OFFICE.

JORGEN S. HAASE, OF CAMDEN, AND SAMUEL M. LANGSTON, OF WENONAH, NEW JERSEY, ASSIGNEES TO SAMUEL M. LANGSTON COMPANY, OF CAMDEN, NEW JERSEY, A CORPORATION OF NEW JERSEY.

CUT-OFF MECHANISM.

1,359,058.

Specification of Letters Patent. Patented Nov. 16, 1920.

Application filed August 22, 1919. Serial No. 319,184.

To all whom it may concern:

Be it known that we, JORGEN S. HAASE, a subject of Denmark, and a resident of Camden, in the county of Camden and State of 5 New Jersey, and SAMUEL M. LANGSTON, a citizen of the United States, and a resident of Wenonah, in the county of Gloucester and State of New Jersey, have invented certain new and useful Improvements in Cut- 10 Off Mechanism, of which the following is a specification.

This invention relates to cut off mechanism particularly adapted for use with comparatively thick stiff sheet material, such as 15 double faced corrugated paper, multiple ply board, or the like, and for use in conjunction with mechanism for delivering or advancing the material without interruption during the cutting operation. The invention 20 relates to that type of cut off mechanism in which the pair of co-acting knives or other cutters move back and forth along the line of travel of the material and cut the latter while traveling in one direction with 25 the material. Our invention involves primarily the means for supporting, operating, and controlling movements of the cutters, and the main object of the invention is to provide a relative movement of the 30 cutters about a pivotal center, which center has a bodily movement in the general direction of the line of travel of the material, whereby an efficient cutting action is secured, rotary or swinging movement utilized 35 instead of reciprocating, and the desired relative speeds of the cutters and back and forth bodily travel is maintained.

In the accompanying drawings, there is 40 illustrated one embodiment of our invention, although it will of course be understood that we do not wish to be limited to the specific construction illustrated except in so far as it is defined in the appended claims.

In these drawings:

45 Figure 1 is an end view of the cut off mechanism.

Fig. 2 is a front view.

Fig. 3 is a plan view.

50 Figs. 4 to 8 inclusive are diagrammatic views, showing the cutters and operating parts; Fig. 4 illustrating the normal or rest

position; Fig. 5 the position at the beginning of the cut; Fig. 6 the position at the end of the cut; Fig. 7 the position after one half revolution from the rest position; and 55 Fig. 8 midway of the return to rest position; and

Fig. 9 is a sectional detail of the cutters.

The machine illustrated, includes a suitable base 10, to which is pivoted a knife or 60 cutter carrier which, as illustrated, includes a pair of upstanding parallel arms 11 connected by a transverse beam or bar 12 to which the knife or cutter 13 is secured. The arms 11 are of such length that they may 65 swing through a comparatively small angle but give the desired length of substantially horizontal movement to the cutter 13. The normal or rest position of the arms is slightly to one side of the vertical, and the 70 movement of the arms carries them to approximately the same distance at the other side of vertical, and by reason of the length of the arms and the angle through which they swing, the path of movement of the cutter 75 13 is substantially horizontal. The arms are illustrated as being mounted at their lower ends upon a rock shaft 14 journaled in bearings 15 on the base 10 but it will of course be evident that any other suitable 80 form of pivotal support might be provided.

Pivoted secured to the cutter carrier above described is a second cutter carrier. As illustrated, the arms 11 have portions 16 extending rearwardly at approximately the 85 elevation of the cutter 13 and to these rearwardly extending portions are pivotally mounted a pair of arms 17 connected together by a transverse beam or bar 18 of the same general character as the bar or beam 90 12 and carrying a somewhat similar cutter 19. The pivotal connection between the arms 11 and 17 may be of any suitable character, as for instance, pivot bolts 20. The distance from these pivot bolts to the cutters 95 13 and 19 is approximately the same, and the cutters are of such character that as the arms swing in respect to each other, the cutters move past each other to shear the intervening material. I have shown the cutters 13 rigidly bolted to but removable from 100 the means 12 and have shown the cutters 19

connected by adjusting bolts 21, whereby the cutters may be properly adjusted in respect to each other or removed for sharpening or repair.

For operating the cutters, there is provided means for swinging the arms 11 back and forth to give the cutters 13 an approximately horizontal movement. The speed of travel of the cutters in one direction is at 10 the same speed as the rate of travel of the material to be cut. It is to be understood that the mechanism is particularly designed for use in connection with a machine which continuously delivers sheet material at a 15 substantially constant speed, and the material being comparatively stiff, such for instance as double faced corrugated board. The delivery mechanism is not shown as obviously it forms no portion of our present invention. The speed of return movement of the cutter 13 is immaterial as is also such portions of the forward movement of the cutter as take place while the cutters are separated and the material is free to 20 pass therebetween. As a preferred mechanism for swinging the arms 11 and cutter 13, there is provided a shaft 22 parallel to the pivots of the arms 11 and having eccentric connections to said arms. These 25 connections are illustrated as a pair of crank arms 23 keyed to the shaft 22 and connecting rods 24 journaled on the crank pins 25, and to pivot pins or stub shafts 26 on the arms 11. These connecting rods are illustrated as being of adjustable length so that 30 the normal rest position of the cutter 13 may be varied. A complete revolution of the shaft 22 will swing the arms 11 and the cutter 13 back and forth through one complete 35 cycle.

As the speed of travel of the cutter 13 during its back and forth movement varies continuously, the operating mechanism for the cutter 13 is such that the cutting operation takes place during that portion of the 40 forward movement of the cutter 13 when it most nearly approximates the speed of the material. The operating mechanism for the cutter 13 also insures the complete separation of the cutters to permit free passage of the material therebetween during the complete return stroke of the cutter 13. This 45 operating mechanism includes a guide which engages with the arm 17 while the latter is being positively carried along with the 50 swinging arms 11. The preferred form of guide is a rotary cam engaging with a projection from the arm 17. As shown, each arm 17 is approximately of bell crank form, 55 that is, it includes a substantially horizontal portion carrying the cutters 19 and a depending portion 27 approximately at right angles thereto, and approximately parallel to the main or body portions of the arms 60 11. The guiding or controlling means for 65

the arm 17 is illustrated as including a shaft 28 journaled in suitable uprights or brackets 29 on the base 10 and carrying a pair of disks 30 having laterally facing cam grooves 31 receiving rollers or projections 70 32 on the depending ends 27 of the arms 17.

The shaft 22 which is mounted on uprights or brackets 33 and the shaft 28 are parallel and are so connected that they make a complete revolution in the same 75 time. The particular design of cam and co-operating parts is such that the shafts 22 and 28 must rotate in opposite directions and at the same speed. This is accomplished by intermeshing gears 34 and 35 of the 80 same pitch diameter on the two shafts. It will of course be evident that with other forms of cam and other relative proportions and positions of the parts, the two shafts might be rotated in the same direction to give the desired effect or might be rotated by variable speed connections, it only being important that the two shafts start from and return to predetermined relative positions which are preferably rest-90 positions in the same time interval.

In order to clearly indicate the successive positions of the parts and the operation of the guide 31, I have shown the parts diagrammatically in a plurality of positions in 95 Figs. 4 to 8 inclusive. The parts at the beginning of a cycle of operations, are in what is preferably a rest position, and are as illustrated in Fig. 4. It will be noted that the cam groove or guide 31 has a portion 31^a 100 substantially concentric with the axis of the shaft 28 and two approximately straight portions 31^b and 31^c, approaching toward and diverging from said axis and are along cords of the circle of the portion 31^a. The 105 curved or concentric portion 31^a extends along somewhat less than 180° and the portions 31^b and 31^c are connected by a second concentric portion 31^d close to the axis of the shaft and extending through about 90°. 110 These two concentric portions 31^a and 31^d in effect constitute stops. The cam or guide 31^a is indicated as a groove but of course either side of the groove might be omitted, if proper means be provided for holding the 115 guided part against the other side.

With the parts in normal or rest position as shown in Fig. 4 the crank arm 23 is approximately at one dead center position and the arm 11 is drawn back to its limiting 120 position toward the source of material to be cut. The roller 32 which forms the guided end of the arm 17 is at the beginning end of the concentric portion 31^a of the guide or cam groove. As the shaft 22 rotates clockwise and the shaft 28 rotates counter-clockwise, the parts move to and through the position indicated in Fig. 5, at which point the cut of the material begins. As the arm 11 swings toward the right from the position 125 130

shown in Fig. 4 it carries with it the pivot pin 20 of the arm 17 but the lower or guided end 32 of the arm 17 is prevented from moving laterally at the same speed. Thus the bell 5 crank arm 17 is forced to swing about its pivot and the upper cutter 19 swings downwardly to and past the cutter 13. It will be noted that the crank arm 23 and the connecting rod 24 are approaching normal to each 10 other at the beginning of the cut. Thus at this period the arm 11 is moving at its highest rate of speed and the cutter 13 is moving at the same speed as the material, and the cutter 19 is also swung down at a 15 corresponding high speed to sever the material. When the crank arm and connecting rod are slightly past normal, as indicated in Fig. 6, the cutting operation has been completed. At this instant the guided end 20 32 of the arm 17 reaches the end of the curve 31^a and enters the substantially straight portion 31^b. It will be noted that the shaft 22 is so positioned in respect to the length of the bell crank arm portion 27 that the guided 25 portion 31^b is approximately horizontal at this instant and the guided portion 32 is caused to make a very rapid horizontal movement with a correspondingly rapid upward movement and separation of the cutters. This separation takes place before the 30 arm 11 reaches the end of its stroke and thus the material may be passing through between the cutters during the slower movement of the arms 11 which takes place when 35 the crank arms 23 are approaching their second dead center position shown in Fig. 7. It will be noted that in this position the guided portion 32 is comparatively close to the axis of the shaft 28 and thus a rotation 40 of the shaft through a comparatively wide angle gives but slight if any movement to the guide 32. With the guide 32 held approximately stationary, any swinging of the arms 11 causes a relative movement of the 45 cutters. When the arm has thus swung through its outward stroke and the shafts 50 22 and 28 have rotated through a half revolution, the cutters have been brought together, severed the material, and have been separated. During the return movement of 55 the arms 11, they pass through the position indicated in Fig. 8 in which the guided portion 32 moves along the cam portion 31^c and holds the cutters separated during the 60 entire return movement. By the time the guided portions 32 of the arm 17 reach the end of the guided portion 31^c, the pivotal center of the arms 17 have also been moved laterally to a corresponding extent and 65 there has been but comparatively slight relative movement of the cutters during the entire return stroke. With the cam illustrated, it is important that it rotate in the direction indicated, namely counter-clockwise, 70 but with a crank arm and connecting rod

or any other equivalent form of eccentric connection, the direction of rotation of the shaft 22 is immaterial.

Power may be applied to the machine through any of the moving parts, although 70 it is preferably applied through the shaft 22 which is nearest to and most conveniently coupled up with the sheet and delivery mechanism so as to insure the proper relative speeds of the cutoff mechanism and the 75 delivery mechanism.

In practice, the cutoff mechanism is operated intermittently and is normally at rest with the parts in the position shown in Fig. 4. The material may freely pass between 80 the two cutters until the desired length of sheet has been fed through and the mechanism then operates to start the cutoff mechanism and operate it through one cycle and back to the rest position. The control of the 85 machine forms no portion of our present invention but it preferably operates some form of clutch which, when engages, will give one revolution and then release. The clutch may be controlled by the delivery machine 90 or by a stop in the path of the advance end of the material being delivered. We have illustrated a sprocket wheel 36 on the shaft 22 and to which may be connected the main drive chain. In practice, the sprocket 36 95 is loose on the shaft 22 and is adapted to be connected thereto by some form of clutch which, as previously stated, will give one revolution and then release. Thus the sprocket 36 may rotate continuously and the 100 shaft 22 and the cutoff mechanism operate intermittently at time intervals depending upon the rate of delivery of the material and the length of sections into which it is to be cut. Of course the sprocket 36 may 105 be keyed to the shaft 22 and the intermittent clutch or other connection be placed farther back in the power transmission train.

Having thus described our invention what we claim as new and desire to secure by Letters Patent is:

1. A cutoff mechanism, including a cutter, a cutter carrier mounted for swinging movement back and forth to move the cutter in the general direction of the line of travel of the material to be cut, a second cutter, a cutter carrier therefor pivotally mounted on said first mentioned cutter carrier, and a rotatable member for effecting a relative movement of said cutter carriers to swing said 115 cutters past each other during the swinging movement of the first mentioned cutter carrier.

2. A cutoff mechanism, including a pivoted arm, a cutter carried thereby, a second arm pivoted to the first mentioned arm, a cutter carried by said second mentioned arm for coöperation with the first mentioned cutter to sever the material, and a member rotatable about a fixed axis for swinging said 120 130

second mentioned arm in respect to the first mentioned arm during the swinging movement of the latter.

3. A cutoff mechanism, including a pivoted arm, a second arm pivoted to the first mentioned arm, a pair of coöperating cutters carried by said arms, and a member rotatable about a fixed axis for effecting the swinging movement of the second mentioned arm in respect to the first mentioned arm during the swinging of the latter.

4. A cutoff mechanism including a pivoted arm, a second arm pivoted to the first mentioned arm, a pair of coöperating cutters carried by said arms, means for swinging said first mentioned arm, and a member rotatable about a fixed axis for effecting the swinging movement of the second mentioned arm in respect to the first mentioned arm during the swinging of the latter.

5. A cutoff mechanism including two members rotatable at the same speed in opposite directions, a pivoted knife carrier operatively connected to one member, and a second knife carrier pivoted to said first mentioned knife carrier and operatively connected to the other member.

6. A cutoff mechanism including two members rotatable at the same speed, a pivoted knife carrier operatively connected to one member, and a second knife carrier pivoted to said first mentioned knife carrier and operatively connected to the other member.

85 7. A cutoff mechanism including two members rotatable in opposite direction, a pivoted knife carrier operatively connected to one member, and a second knife carrier pivoted to said first mentioned knife carrier and operatively connected to the other member.

8. A cutoff mechanism including two rotatable members, a pivoted knife carrier operatively connected to one member, and a second knife carrier pivoted to said first mentioned knife carrier and operatively connected to the other member.

9. A cutoff mechanism including two rotatable members, a pivoted knife carrier, a second knife carrier pivoted to the first mentioned knife carrier, eccentric driving connections between one of said carriers and one of said members, and cam connections between the other of said carriers and the other 55 of said members.

10. A cutoff mechanism, including a pivoted knife carrier, a second knife carrier pivoted to the first mentioned knife carrier, means for swinging said first mentioned knife carrier back and forth, and a rotatable cam having direct engagement with said second mentioned knife carrier.

60 11. A cutoff mechanism, including a pivoted knife carrier, means for swinging said carrier back and forth, a second knife car-

rier pivoted to the first mentioned knife carrier, and a guide groove engaging with said second mentioned knife carrier for controlling the relative movements of the knife carriers during the swinging movement of the first mentioned carrier.

70 12. A cutoff mechanism, including a pivoted knife carrier, means for swinging said carrier back and forth, a second knife carrier pivoted to the first mentioned knife carrier, and a rotatable member having a guide groove engaging with said second mentioned knife carrier for controlling the relative movements of the knife carriers during the swinging movement of the first mentioned carrier.

75 13. A cutoff mechanism, including a substantially vertical arm pivotally supported at its lower end and carrying a cutter at its upper end and presenting a lateral extension, a bell crank arm pivoted to said extension and having a horizontal portion and a depending portion, a cutter carried by said horizontal portion for coöperating with said first mentioned cutter, means for swinging said first mentioned arm about its pivot, and means engaging with the depending end of the second mentioned arm for effecting a relative movement of said cutters during a swinging movement of said first mentioned arm.

80 14. A cutoff mechanism, including a substantially vertical arm pivotally supported at its lower end and carrying a cutter at its upper end and presenting a lateral extension, a bell crank arm pivoted to said extension and having a horizontal portion and a depending portion, a cutter carried by said horizontal portion for coöperating with said first mentioned cutter, means for swinging said first mentioned arm about its pivot and a rotatable member presenting a cam surface engaging with the depending end of the second mentioned arm for effecting a relative movement of said cutters during a swinging movement of said first mentioned arm.

85 15. A cut off mechanism including a cutter pivotally supported to oscillate about a fixed center spaced from the path of movement of the material to be cut, and having a cutter movable back and forth along an arc approximately tangent to said path, a second cutter carrier pivotally connected to said first mentioned cutter carrier at a point 115 spaced from said cutter in the general direction of the path of the material, and having a cutter movable up and down in respect to the first cutter along an arc approximately at right angles to said path, a crank shaft rotatable about a fixed axis, a link connecting said first mentioned cutter carrier and the crank of said crank shaft for oscillating the first mentioned cutter carrier, 120 130

and means for swinging said second mentioned cutter carrier during said movement of said first cutter carrier.

16. A cutoff mechanism, including a pair of parallel shafts geared together for simultaneous rotation in opposite directions, a pivoted cutter carrier, a second cutter carrier pivoted to the first mentioned carrier, and separate means for connecting said shafts

and said carriers for effecting the bodily movement and the swinging movement of said second mentioned carrier.

Signed at Camden, in the county of Camden and State of New Jersey, this 25th day of July, A. D., 1919.
